UNITED STATES PATENT OFFICE.

JAMES M. EDWARDS, OF NEW YORK, N. Y.

GATE MECHANISM.

1,311,332.

Specification of Letters Patent. Patented July 29, 1919.

Application filed May 1, 1918. Serial No. 231,897.

To all whom it may concern:

Be it known that I, JAMES M. EDWARDS, a citizen of the United States, residing at New York city, in the county of New York and State of New York, have invented certain new and useful Improvements in Gate Mechanism, of which the following is a specification.

This invention comprehends certain new and useful improvements in movable gates for controlling the flow of comminuted or pulverulent materials or substances such as grain, sugar, coffee, meal and the like, which have a tendency to clog in passing from a bin or hopper into a spout or receptacle, the invention also being applicable for use in connection with the control of hot or cold air, steam, or other fluids, as will be hereinafter more definitely specified.

20 The invention has for its primary object a simple, durable and efficient construction of movable gate, the parts of which are so formed and arranged that the slide forming the movable part of the gate construction will not be liable to become deformed with a consequent tendency to bind, and wherein the construction of the slide, together with the housing in which it moves, are such as to facilitate at all times the opening and closing movement, as required, and positively preclude this liability to bind or stick.

35 A further object of the invention is an improved gate of this character, which is provided with a cut-off projecting into the opening across which the slide is mounted to move, and so positioned and otherwise arranged and correlated with the slide, that all liability of the material to clog or catch or to be cut or crushed, will be effectually prevented.

40 And the invention also aims to generally improve devices of this class so as to render them more useful and commercially desirable.

45 With these and other objects in view, as will more fully appear as the description proceeds, the invention consists in certain constructions, arrangements and operations of the parts that I shall hereinafter fully describe and claim.

50 For a full understanding of the invention, reference is to be had to the following description and accompanying drawing, in which—

Figure 1 is a vertical longitudinal section of the device, 55

Fig. 2 is a horizontal sectional view,

Fig. 3 is a vertical section on the line 3—3 of Fig. 1, and

Fig. 4 is a detail perspective view of the 60 slide.

Corresponding and like parts are referred to in the following description and designated in all of the views of the accompanying drawing by like reference characters. 65

Referring to the drawing in which, for the purposes of illustration I have shown a conventional form of bin or hopper designated 1 and provided with the usual collar 2, the numeral 3 designates the casing or 70 housing of my improved gate, said casing being formed in complementary members or castings designated 4 and 5 respectively. In the present embodiment of the invention, the device is shown as disposed in a relatively vertical position, and hence, for the purposes of distinction or identification, I shall hereinafter refer to the member 4 of the casing as the upper member and the member 5 as the lower member, but it is to 75 80 be understood that these terms are merely relative and not restrictive in any way.

The upper member 4 of the casing is, in the present instance, formed with a thimble or collar 6 secured in any desired way to 85 the collar 2 of the bin or hopper 1, and the lower member 5 is correspondingly formed with a depending collar designed to be secured in any desired way to a spout or receptacle through or into which the 90 material is intended to flow.

The two members 4 and 5 may be secured together in any desired way as, for example, by means of screw bolts 8 or similar fastening devices, so that they are held together in superposed relation with their openings defined by the collars 6 and 7 in alignment or registry with each other, and the lower member 5 is formed with longitudinally extending, relatively raised side 100 edges 9 which abut against the lower surface of the upper member 4, whereby a transversely extending space 10 is formed for the reception or accommodation of the slide 11 of the device. The lower member 105 5 is further formed with longitudinally extending openings 12, spacing the medial portion of said member from the raised side

edges 9, and in the upper face of the lower member longitudinal grooves 13 are formed, said grooves defining the adjoining side walls of the openings 12 as clearly illustrated in the drawing.

5 The slide 11 is formed with longitudinally extending side flanges 14, disposed in angular relation to the body portion of the slide, and serving to strengthen the same and to especially prevent the slide from becoming warped, bent, or otherwise formed, and these flanges 14 work freely in the openings 12 and with their edges moving in the grooves 13 as shown. The slide 11 may be provided 10 with any desired construction or design of handle 15, and may be moved manually or otherwise according to the requirements of the case. It is to be observed that the handle or flange 15 constitutes an abutment, to contact with the enlargement at the lower end 15 of the collar 6, thereby limiting the gate in its movement toward a closed position.

Disposed within the collar 6 and preferably forming an integral part thereof, is a 20 cut-off 16, which projects into the opening formed in and extending through the casing 3, with its lower flat face or surface terminating flush with the upper boundary of the space 10, across which the slide 11 is adapted 25 to move, whereby as will be manifest, when the slide is moved inward to close the opening, its innermost edge will first meet the cut-off 16, so as to stop the flow of material and permit the material that would otherwise be caught at this point to drop downwardly into the spout or receptacle, all clogging of the parts and any crushing or cutting of the material being thereby positively precluded.

30 40 From the foregoing description in connection with the accompanying drawing, the operation and practical advantages of my improved gate will be apparent. As hereinbefore indicated, while I have illustrated the device as applied to a bin or hopper for grains or other granular comminuted or pulverulent substances or materials, yet the invention is not limited to such use and is of equal applicability with the same incidents 45 of advantage, for use in controlling the passage of hot or cold air or steam through a blast or other pipe, in which event all binding of the slide consequent upon its corrosion will be prevented, for it is to be understood, that the slide is permitted some play 50 within the space 10 and openings 12 so that it will not be liable to catch or stick even

though rusted, while at the same time the flanges 14 assist in facilitating the movement of the slide and prevent it from becoming 60 bent or otherwise deformed, which would cause it to bind.

While the accompanying drawing illustrates what I believe to be the preferred embodiment of my invention, it is to be understood that various changes may be made in the construction, arrangements and proportions of the parts without departing from the scope of the invention as claimed.

70 What is claimed is:

1. In a gate mechanism for grain chutes the combination with adjacent conduit sections, the adjacent parts of which have correspondingly shaped rectangular flanges, the inner portion of one of the flanges having 75 diametrically oppositely disposed parallel channel guides, the inner wall of said guides being fore-shortened and offset below the flanged end of the other section, of a slide plate mounted for transverse movement between the sections and provided with depending opposite flanges engaging and resting upon the bottoms of the channel guides for holding the slide plate in spaced relation between the sections and out of contact with 80 the adjacent ends of the sections.

2. In a gate mechanism for grain chutes, the combination with a pair of axially adjoining conduit sections, the adjoining ends thereof being provided with flanges of corresponding shape, diametrically opposite portions of the end of one section adjacent its flange having opposite parallel channel guides, the inner walls of said guides at diametrically opposite points being fore-shortened and off-set with relation to the outer walls of the channel guides, the end of said section at diametrically opposite points at right-angles to the channel guides being flush with the fore-shortened off-set inner 95 walls of the channel guides, whereby a grain gate receiving space open at both ends is formed, of a grain slide gate comprising a plate mounted for transverse movement in said gate receiving space and provided with opposite parallel flanges fitting loosely in the channel guides, whereby the edges of the flanges of said gate may engage with the bottoms of the channel guides, thereby permitting free movement of the grain gate in 100 105 said space.

110 In testimony whereof I affix my signature.

JAMES M. EDWARDS.
